CLAIM

The ornamental design for a support base for a desk set or similar article, as shown and described.

DESCRIPTION

FIG. 1 is a top perspective view of a support base for a desk set or similar article showing my new design in the form of a paper weight;

FIG. 2 is a rear elevational view, the front view being a mirror image thereof;

FIG. 3 is a left side elevational view, the right side being a mirror image thereof;

FIG. 4 is a top plan view;

FIG. 5 is a bottom plan view; and

FIG. 6 is a top perspective view of a second embodiment of my new design in the form of a writing instrument holder.

FIG. 1

FIG. 4

FIG. 5

FIG. 2

FIG. 3

FIG. 6
